COAXIAL SWITCHES AND SYSTEMS FOR MICROWAVE SYSTEMS WHICH MAY INCLUDE THOSE IN WHICH SIGNAL FLOW IN UNUSED PATHS IS PREVENTED BY DIMENSIONING FOR CUTOFF OF WAVEGUIDE MODE

Sherman A. Rinkel, Bethpage, N.Y., assignor to General Microwave Corporation, a corporation of New York

Filed Dec. 3, 1963, Ser. No. 327,707

17 Claims. (Cl. 333—7)

This invention relates to coaxial switches and systems, and in particular to such switches for microwave radio frequencies.

In known microwave coaxial switches, their construction has been such that they have not been fully effective in suppressing signals through unselected transfer paths. For example, signal leakage on the order of 40-70 db is characteristic of conventional RF coaxial switches. Moreover, it has been found that undesirable impedance mismatches occur after the switching operations that result in spurious reflected signals in the standby circuits. Multi-position coaxial switches generally employ rotary mechanisms that are stepped through successive intervening positions to a selected one, rather than moved directly thereto, so that the selection time includes that of rotating the switch pole through all intervening positions.

It is therefore among the objects of this invention to provide a new and improved coaxial microwave switch.

Another object of this invention is to provide a new and improved coaxial microwave switch capable of suppressing or attenuating the signal being propagated by about 100 db or more in the unselected transfer path or paths.

Another object of this invention is to provide a new and improved programmable coaxial switching system for selectively switching different combinations of transfer paths into a circuit.

Another object of this invention is to provide a new and improved programmable coaxial attenuator for selectively switching different attenuations into a circuit over a broad range and with high accuracy.

Another object of the present invention is to provide a new and improved coaxial microwave switch which is effective to ensure impedance matches to the various transfer paths under operating conditions.

In one embodiment of this invention, a metallic housing is provided having one or more passages, in each of which a rod reciprocates. Each rod has at least one conductive portion which engages different combinations of contacts when the rod is moved from one position to another. The wall of each passage surrounding the conductive portion of the rod forms a coaxial shield to provide a coaxial connection between the contacts in engagement therewith. The wall of the passages surrounding non-conductive portions of the rod functions as a waveguide beyond cutoff with respect to the wavelengths of the signals being switched to ensure a high attenuation of signals and essentially block transmission thereof to contacts not connected to the conductive portions.

In accordance with a feature of this invention, a plurality of such passages are provided and various circuits are provided in other passages within the housing and connected to certain ones of the contacts. Thereby, the switch may be operated selectively connecting these circuits between input and output terminals. In accordance with another feature, different electrical circuits are connected in the other passages, and the switch is effective to connect a selected one of said circuits between input and output terminals.

In accordance with another feature of this invention, the coaxial switch rod has a plurality of conductive por-

tions, and different combinations of contacts are connected to the conductive portions in different operating positions of the switch rod.

In accordance with another feature of this invention, a coaxial switch of the type described is connected in a system in which at least one signal source is connected to a switch terminal and at least one load circuit is connected to another switch terminal. In all operating positions of the switch, both the source and load circuit are connected through the switch to their respective characteristic terminating impedances.

In accordance with another feature of this invention, a system of coaxial switches of the type described is provided in which the switches are connected in cascade with the output terminal of one being connected to the input terminal of the next and so on. In this fashion, a signal source connected to the input terminal of the first switch may be connected to any one of a plurality of the output terminals of the second such switch, and so on, in one embodiment of the invention. In another embodiment of the invention, employing a plurality of passages in each switch, different combinations of circuit elements within the switches are connected in series by selective, combinatorial operation of the switching rods.

The foregoing and other objects of this invention, the features thereof as well as the invention itself, may be more fully understood from the following description when read together with the accompanying drawing, in which:

FIG. 1 is a partially sectional view in front elevation of a coaxial switch and attenuator system embodying this invention taken on a vertical plane through the center thereof and along the line 1—1 of FIG. 2;

FIG. 2 is a sectional view along the line 2—2 of FIG. 1;

FIG. 3 is an enlarged fragmentary sectional view of a sliding contact portion and is taken along the line 3—3 of FIG. 1;

FIG. 4 is a schematic representation and circuit diagram of a plurality of the coaxial switches and attenuators of FIG. 1 connected in cascade and in a circuit;

FIG. 5 is a schematic representation and circuit diagram of another coaxial microwave switch and circuit embodying this invention;

FIGS. 6A and 6B are schematic representations and circuit diagrams under different switch-operating conditions of another form of this invention; and

FIGS. 7A and 7B are schematic representations and circuit diagrams under different switch operating conditions of still another form of this invention.

In the drawing, corresponding parts are referenced throughout by similar numerals.

In FIGS. 1 to 3, a coaxial switch and attenuator unit 10 comprises a metallic (e.g. aluminum) housing 12 consisting of two mating metal sections 14 and 16 which are removably fastened together in a suitable fashion, for example, by means of bolts 18. Dowel pins 20 are provided in diagonal corners of one of the sections 16 to mate with corresponding holes in the other section 14 to ensure proper mating relationship of the two sections.

Each of the sections 14 and 16 is similarly formed and provided with a pair of semi-cylindrical countersunk passages 22. The latter extend from the outer opposite sides of each section to a second pair of semi-cylindrical passages 24, respectively, and the latter are at right angles to the former and extend for most of the length of the housing section. Two other semi-cylindrical passages 26 and 28 are formed between the passages 24 adjacent to opposite ends thereof. In addition, an enlarged rectangular recess or passage 30 is provided at the lower ends of the passages 24 and communicates therewith, within which certain parts move as is described herein-

after. When the housing sections 14 and 16 are connected together in mating relationship, the corresponding semi-cylindrical passages mate to form cylindrical passages, and the rectangular passages likewise mate.

To coaxial connectors generally indicated at 32 and 34 have the usual conductive outer shields 33 and 35 and concentrically spaced tubular inner conductors 37 and 39 fixed therein. The connectors 32 and 34 are inserted in the outer ends of the passage 22 and fastened to the opposite sides of the housing 12. The outer shields of the connectors 32 and 34 make electrical connection with the housing 12, and the inner conductors 37 and 39 of those connectors 32 and 34 make electrical connection at their ends with rods 36 and 38, respectively, which extend along the axes of the passages 22. Dielectric beads 40 surround the rods 36 and 38 within the passages 22 to insulate the rods from the surrounding conductive housing. The rods 36 and 38 are identical and are fastened in position by means of suitable non-conductive pins 42 extending therethrough into the adjacent housing wall.

The inner ends of the rods 36 and 38 are enlarged and bifurcated (as shown in FIG. 3). The bifurcated ends 44 and 56 function as sliding resilient contacts and engage respective conductive sections 46 and 58 on rods 48 and 60. These rods are coaxially and reciprocatingly mounted within the passages 24.

The rods 48 and 60 function as switching elements and in a preferred form are fabricated of dielectric material, such as polystyrene, nylon or a suitable plastic, with conductive coatings formed around the central portions thereof to form the conductive sections 46 and 58. Sections 50 and 51 on either end of the rod 48 and sections 52 and 53 on rod 60 function as non-conductive or insulating sections of the switching rods. These rods are coaxially centered within the cylindrical passages formed by the mating semi-cylindrical passages 24 by means of suitable insulating spacer beads 54 at each end of the passages 24.

The switching rods 48 and 60 are each preferably made of a solid dielectric material such as polystyrene or nylon, and the conductive portions 46 and 58 are metallic surfaces formed, for example, by a conductive film of silver deposited in a recess around the central periphery of the rods. Thereby, a substantially continuous outer surface with the remainder of the switching rod is provided to ensure a smooth transitional surface as the rods move within the contacts 44 and 56.

The insulating beads and sleeves 40 and 54 are preferably annular beads which may be made of Teflon or similar material that has a low electrical loss and provides a good bearing surface.

The lower ends of the switching rods 48 and 60 are fixedly connected to opposite ends of a yoke or cross-member 62. The yoke 62 moves up and down within the rectangular recess 30 in the housing 12 and thereby actuates in unison the rods 48 and 60. Fixed to the midpoint of the yoke 62 is a driving armature shaft 64 which passes through a bushing 66 fitted in a cylindrical passageway in the lower end of the housing sections 14 and 16. The shaft 64, in turn, is actuated downward by the selective energization of a solenoid 67 by a suitable control current from a source 68 and is restored to an upward position by a suitable biasing spring 69 when the solenoid is deenergized.

A guide rod 70 has its upper and lower ends fixed within the housing section 16 on opposite sides of passage 30, and it passes through an aperture in yoke 62. This rod prevents rotation of yoke 62 about the axis of shaft 64 during its upward and downward movement. The yoke 62 is provided with an adjustable set screw 72 which impinges upon the lower wall of recess 30 and a screw 74 which may be adjustable and which impinges upon the upper wall thereof; both screws function as limit stops. Thereby, the switching rods 48 and 60 are

properly positioned with respect to the contacts 44 and 56 (and also with respect to certain other contacts) in each of their two extreme positions.

In the form of the invention shown in FIG. 1, two electrical paths are provided within the passages 26 and 28. These paths may have any desired electrical characteristics. In the form of the invention shown in FIG. 1, the path within passage 26 comprises a "T-pad" although it should be understood that many other types of electrical circuits such as pi-networks, etc. may alternatively be employed therein.

Within passage 26, the T-pad consists of a tubular conductive member 80 having its outer surface in conductive contact with the passage wall. Member 80 is formed of two threaded parts, one threaded within the other (as shown by the zig-zag lines in the sectional view of FIG. 7) which parts form spaced shoulders to retain the edge of a disc resistor 82 centrally and internally between them. Two rod resistors 84 and 86 are fixed axially within member 80 and spaced therefrom. The inner ends of the rods 84 and 86 conductively engage the center of the disc 82 on opposite sides thereof, and the outer ends are fastened conductively to bifurcated contacts 88 and 90, respectively. These contacts 88, 90 are similar in construction to contact 44 and are fixed within member 80 by suitable insulating pins. When the switch rods 48 and 60 are in the lower position shown in FIG. 1, the contacts 88 and 90 engage the non-conductive sections 50 and 52, and in the upper position, the conductive surfaces 46 and 58, respectively. The T-pad thus consists of the two series resistors 84 and 86 connected in circuit with their junction connected to ground (the metallic housing) via the disc resistor 82.

There is also provided a second electrical path within the passage 28, which includes a dielectric sleeve 92 through which a conductive rod 94 extends. The conductive rod 94 is enlarged at each end and bifurcated to form contacts 96 and 98 which generally are similar to contact 44. These contacts 96 and 98 engage the conductive surfaces 46 and 58 when the yoke 62 is in its lower extreme position as shown in FIG. 1, and the non-conductive sections 51 and 53 in its upper position.

When the yoke 62 is in its lowest position (as shown in FIG. 1), signals coming into coaxial connector 32 pass via contact 44, conductive section 46 of the switching rod 48, contact 96, rod 94, contact 98, conductive section 58, contact 56, and out through connector 34. Thereby, a straight-through connection is made, and the housing walls of the cylindrical passages provide coaxial shields for the inner conductors between the connectors 32 and 34.

With the yoke in the upper position, incoming signals are applied to the conductive section 46 of the switching rod 48 via the contact 44. The signal is propagated along the conductive section 46 and applied via contact 88 to the T-pad resistors 84, 82, 86, and thence via contact 90, conductive section 58, and contact 56 to connector 34. The walls of all of the cylindrical passages provide coaxial shields for all of the conductors between the two coaxial connectors 32 and 34.

Regardless of which electrical path is selected, leakage of the signal through the other path is attenuated by approximately 100 db or more. This is accomplished by providing that the conductive walls of the passages surrounding the non-conductive portion of the rods 48 and 60 have dimensions which make them waveguides beyond cutoff with respect to the applied signal frequencies. Thus, when the yoke 62 is in the position shown in FIG. 1, the walls of the passage 24 surrounding the non-conductive portion 50 between contacts 44 and 88 have a length which is more than three times the diameter of the passage 24. For a distance along this section of the wall equal to the diameter, there is approximately a 32 db attenuation at the band of frequencies applied. The presence of the dielectric rod 50 in this region effectively

lowers the cutoff wavelength, and the diameter of the surrounding passage wall is actually made somewhat smaller to ensure a cutoff characteristic. When the yoke 62 is moved to the uppermost position, the wall of the passage 24 surrounding the dielectric rod 51 between the contacts 44 and 96 similarly constitutes a waveguide beyond cutoff.

Thus, with respect to the unselected path, the leakage is attenuated 100 db or more in each of the two sections of waveguide beyond cutoff. This leakage signal of 100 db is but one practical value, and it may be made as large as desired by simply lengthening the cutoff tubes. Practical limitations exist due to other leakage paths; e.g. currents may flow at the junction of the two halves of the housing, and connector leakage may exist. Practically, for a desired T-pad attenuation of 100 db, the leakage path attenuation should exceed this by at least 20 db, and preferably 30 db to eliminate significant errors in the attenuation of the desired path. With a leakage path attenuation equal to the desired attenuation, extremely large errors may result; this condition is avoided in practice by a suitable choice of parameters so that the leakage path attenuation is sufficiently larger than the desired attenuation.

Any desired circuits of different characteristics may be placed in the transfer passages 26 and 28. For example, filter circuits, diode mixers, limiters or clippers may be used. Moreover, both transfer passages may have different circuits other than a straight-through path.

FIG. 4 shows two of the coaxial switches of FIG. 1 connected in cascade. They may be used, for example, as two-position switches in a binary configuration. In this case the electrical paths of the switches are furnished with attenuators such as T-pads constructed to introduce binary values of attenuation, i.e., 1, 2, 4, 8, for successive stages. By appropriate combinatorial selection of the fixed attenuations, any desired attenuation value can be connected in circuit in a single switching operation for each stage and with all of the operations occurring at the same time. Thereby, a high-speed, programmable system is provided for selecting any desired value of attenuation (or other electrical characteristic).

In FIG. 4, as in the rest of the figures to follow, the novel switches described above are shown schematically. Parts representing those described in FIG. 1 are referenced by similar numerals. Pairs of vertical lines represent the conductive walls of the passages 24 depicted in FIG. 1, and the horizontal line pairs represent other related conductive passage walls or shields. The resistors schematically indicated within those pairs of lines represent the non-conductive portions 50, 51, 52 and 53 of the switching rods (and in each case represent a waveguide beyond cutoff), and the lines 46 and 58 represent the corresponding conductive sections of the switching rods. The resistors 82, 84, 86 represent the T-pad in the first conductive path, and the arrowheads represent the contact members which engage the conductive and non-conductive sections of the switching rods. Other parts of the apparatus 10 are also numbered to correspond to their counterparts in FIG. 1.

A source 110 is connected to the input connector 32 of a first switch 10, and a matched or characteristic load impedance, illustrated schematically as the resistor 120, is connected to the output connector 34' of a second switch 10', corresponding parts of which are referenced by similar numerals with the addition of a prime ('). The switches 10 and 10' may be constructed in separate housings or they may be formed in the same housing. In the latter case, the coaxial coupling 111 between the output of one and the input of the other may be formed in another passage in the housing similarly as with the coupling 94. The corresponding parts of the two switches 10 and 10' are the same in construction, except for the resistors in the T-pad. The T-pad resistors 99, 100, and 101 are chosen to have a different attenuation character-

istic from the switch 10 T-pad. For example, the T-pad in switch 10 may introduce a one db attenuation, and the T-pad in switch 10' may introduce two db or any other selected attenuation. If one db attenuation is desired, switch 10 is actuated to the attenuating path by its solenoid 67, whereas switch 10' is in the nonattenuating position. If two db attenuation is desired, the positions of the rods in switches 10 and 10' are reversed; and if three db attenuation is desired, both are actuated to the attenuating position. Any desired additional number of such switches having successive binary or other characteristics may be similarly disposed in the same housing or separately to achieve any desired attenuation characteristics. The invention is not limited in its application to the use of attenuators in one or both of the two transfer paths of each switch. Other circuits may be employed to achieve desired combinations of characteristics.

In the switches of both FIGS. 1 and 4, the source 110 and load 120 are connected in circuit in all positions of the switches so that both are terminated in their characteristic impedances in all switch positions.

Another coaxial microwave switch and circuit embodying this invention is shown in FIG. 5. Here the switch is constructed so that the switching rods can be separately moved, and rods may be used that have more than one conductive section. FIG. 5 is an example of such a device used as a single pole-four throw switch having three rods generally indicated by the numerical designations 102, 103, and 104; 103 and 104 are coupled so as to move in unison, and may be formed as a single rod with the conductive surfaces properly located. There are also two signal paths 105 and 106 which contain straight-through conductors. The source 110 applies an input signal via input coaxial connector 32 to the rod 102. Four output coaxial connectors 112, 113, 114, and 115 are also connected to contacts constructed to engage the rods 103 and 104 as shown.

The solenoids 67" and 67"" determine the upward or downward positions of the rods 102 and 103, respectively. In the positions of the rods shown, the source 110 is connected via the conductive portion of rod 102, the lower signal path 106, and the conductive portion of rod 104 to output terminal 118, to which a matched load 120 is connected. If solenoid 67"" is energized so as to pull rods 103 and 104 down, the source 110 is then coupled to terminal 119. If rod 102 is up and rods 103 and 104 are also up in the position illustrated, the source 110 becomes coupled to the terminal 116 via the conductive portion of rod 102, the upper signal path and the conductive portion of the rod 103. If, while rod 102 is in the up position, rods 103 and 104 are down, source 110 is coupled to output terminal 117. In all positions, as explained above, the walls of the passages around the non-conductive portion of the rods 102, 103, and 104 between the input contact and the contact for the unselected path are dimensioned to function effectively as waveguides beyond cutoff at the band of frequencies supplied. The details of construction of this switch will be readily apparent from the foregoing description.

Another form of the present invention is shown schematically in FIGS. 6A and 6B which represent two different switching positions of the same switch. In this embodiment, there is a source 110 coupled to an input connector 111 as in the previous example, but within the single passage there is disposed a rod 121 having two conductive sections 122 and 123 spaced from one another by an intermediate non-conductive section. There are four output contacts represented by the arrows pointing toward the left and four output connectors 124, 125, 126 and 127. The output at connectors 124 is connected to a characteristic impedance element 128 which provides a proper termination for signals from the load 130 connected to output connector 125. Similarly, the characteristic impedance element 129 coupled to connector 127 provides a proper termination to the load 131. In the

position of the switching rod 121 shown in FIG. 6A, the source 110 is coupled via conductive section 122 and connector 125 to load 130. At the same time, the conductive portion 123 connects the unselected load 131 to the terminating impedance 129. In FIG. 6B, the rod 121 has been elevated to its uppermost position so that the source 110 is now connected via the conductor 123 to the load 131 whereas load 130 is connected to its terminating impedance 128. Thus, in either position of the switching rod, the source is connected to a characteristic load impedance, and the loads are themselves connected to characteristic terminating impedances. Thereby, reflections due to mismatches are avoided in all positions of the switch. The switching rods 102, 103, and 104 of FIG. 5 may be constructed similarly to those of FIGS. 6A and 6B to have pairs of conductive sections and additional contacts therefor; thereby, loads at the output terminals may be properly terminated in all switch positions. As in the previous examples, the portion of the passage walls surrounding the non-conductive part of the rod between the input contact and the contact for the unselected path is dimensioned to constitute effectively a waveguide beyond cutoff.

Another form of the invention is shown in FIGS. 7A and 7B which schematically represents a switch construction that may be used as a transfer switch of the type employed in antenna applications. This switch 10" is similar to the switch 10 of FIG. 1 except that the two electrical signal paths employ inner conductors 94 and 94' which are essentially non-resistive at the band of frequencies involved. There are also two switching rods 121 and 121' which may be substantially identical to that of FIGS. 6A and 6B. The switching rods are actuated in unison by a yoke 62. There are two input connectors 111 and 111' coupled to terminals 132 and 133. There are also two output connectors 134 and 135 connected to terminals 136 and 137. In the position shown in FIG. 7A, the terminals 132 and 133 are isolated from each other and are coupled via conductors 94' and 94, respectively, to the output terminals 136 and 137. In the position of the switch shown in FIG. 7B, the terminals 132 and 133 are effectively isolated from the others and are connected together, as are the terminals 136 and 137. Thus, sources or loads connected to the various terminals are properly terminated in both positions of the switch.

The switch construction of FIG. 1 is generally applicable to each of the other switch arrangements described above, with the modifications required in each instance. The straight switching rod construction that is illustrated is generally preferred. However, the invention is not limited thereto and may also be constructed with generally annular rods that reciprocatingly turn in annular passages formed in a metal housing. Switching contacts would engage the rods at appropriately spaced points in a manner similar to that described above to effectuate a coaxially shielded connected path and waveguide beyond cutoff unconnected path.

There are many other variations possible such as the connection of the elements of FIG. 5 to form a single pole-n throw switch, or by ganging switches, an n-pole, n-throw switch. Of course, any desired number of rods having any desired number of conductive portions may be used with any appropriate number of contacts to provide other switching devices, patterns, and circuits. The electrical paths may have any desired circuitry or other electrical characteristics. The movement of the rods may be accomplished by electro-magnetic means as shown, by manual means, by hydraulic actuation, etc. Furthermore, either the rods themselves may be moved or the housing may be moved, or both. As many such arrangements of applications will occur to those skilled in the art upon perusing the specification and drawings herein and these applications do not depart from the essence of the invention, this invention should be limited solely by the claims which follow.

What is claimed is:

1. A coaxial microwave switch for use with a source of signals within a certain frequency band, said switch comprising: means forming first and second passages each having conductive walls, first and second rods respectively movably mounted within said first and second passages, each of said rods having at least one conductive section, first and second contacts respectively engaging the conductive sections of said first and second rods, a plurality of electrical paths each having means for contacting said conductive sections in selected operating positions of said rods, and means for reciprocating said rods in unison to connect said electrical paths between said contacts, the walls of said passages surrounding said conductive sections providing coaxial shields therefor and the walls of said passages not surrounding said conductive sections being dimensioned to function as waveguides beyond cutoff with respect to said band of frequencies.

2. A coaxial microwave switch as recited in claim 1 wherein said rod reciprocating means is effective to connect one or another of said electrical paths between said contacts.

3. A coaxial microwave switch as recited in claim 2 wherein said electrical paths have different electrical characteristics.

4. A coaxial microwave switch as recited in claim 3 and further comprising a second switch of substantially similar construction as the first switch, the second contact of one of said switches being connected to the first contact of another thereof.

5. A coaxial microwave switch as recited in claim 1 wherein a plurality of said first and a plurality of said second contacts are provided, and said rod reciprocating means is effective to connect each of said electrical paths between one each of said first and second contacts and alternatively to connect said first contacts together and said second contacts together.

6. A coaxial switch for use with a source of signals within a certain frequency band, said switch comprising: a conductive housing, first and second substantially parallel passages therein, third and fourth passages therein which are substantially parallel to one another and located between and transverse to said first and second passages and communicate therewith, first and second rods respectively movably mounted within said first and second passages, each of said rods having a conductive surface section disposed between non-conductive surface sections, fifth and sixth passages communicating with said first and second passages respectively and extending to the outside of said housing, input means for connection to a coaxial line, said input means being disposed within said fifth passage and including an input contact for engaging the conductive section of said first rod, output means disposed within said sixth passage for connection to a coaxial line and including an output contact for engaging the conductive section of said second rod, a first electrical path disposed in said third passage, said path including two contacts for engaging said first and second rods, respectively, a second electrical path disposed in said fourth passage and including two contacts for engaging said first and second rods, respectively, said electrical paths having different electrical characteristics, and means for reciprocating said rods in unison into first and second operating positions, said first electrical path being, in said first position, connected via said conductive sections between said input and said output means, said second electrical path being, in said second position, connected via said conductive sections, between said input and output means, the walls of said passages surrounding said conductive surface sections providing coaxial shields therefor, and the wall of said passages surrounding said non-conductive surface sections between said input contact and the contact of the path not selected being dimensioned to function as waveguide beyond cutoff.

guides beyond cutoff with respect to signals from said source.

7. The switch according to claim 6 wherein said first electrical path includes a signal attenuation circuit and wherein said second electrical path has essentially no attenuation.

8. The coaxial switch according to claim 7 wherein said means for reciprocating said rods includes a rigid yoke coupled to said rods and a shaft connected to said yoke and extending from the interior of said housing to the exterior thereof for actuation.

9. A switching system for microwave signals, said system comprising: a source of microwave signals within a certain frequency band; a plurality of coaxial microwave switches in series, each of which includes: first and second passages each having conductive walls, first and second rods respectively movably mounted within said first and second passages, each of said rods having at least one conductive section disposed between non-conductive sections, an input means having an input contact for engaging at least one of said conductive sections of said first rod, an output means having an output contact for engaging at least one of said conductive sections of said second rod, a plurality of electrical paths each having means for contacting conductive sections of both rods, each path having selected electrical characteristics, and means for moving said rods in unison into selected operating positions thereby to connect selected ones of said electrical paths between said input and output contacts, said switches being coupled so that the input means of the first of said switches is connected to said source and the input means of subsequent switches are respectively coupled to the output means of the preceding switch, the output means of the last switch being connected to a load circuit, said switches being arranged so that upon operation of selected ones of said moving means, predetermined combinations of said electrical paths are connected in a series circuit between said source and said load, the walls of the passages surrounding the conductive sections of each switch providing coaxial shields therefor, and the walls of said passages surrounding said non-conductive sections being dimensioned to function as waveguides beyond cutoff to signals within said frequency band.

10. The switching system according to claim 9 wherein in each switch has two paths, wherein one path in each switch has substantially zero attenuation and wherein all the second paths in said switches have substantial attenuation characteristics which are binary-related to one another.

11. A coaxial microwave switch for use with signals within a certain frequency band, said switch comprising: first and second passages each having conductive walls, a first rod means disposed within said first passage, a second rod means disposed in said second passage, all of said rod means being movably mounted within their respective passages, said first rod means having at least one conductive section and said second rod means having a plurality of conductive sections disposed between non-conductive sections, input means communicating with said first passage and including an input contact which engages a conductive section of said first rod means, a plurality of output means communicating with said second passage, each of said output means including an output contact for engaging a different one of the conductive sections of said second rod means, a plurality of electrical paths each having a contact which engages said first rod means and each also having a contact which engages at least one of the conductive sections of said second rod means, each of said paths having predetermined electrical characteristics, and means for reciprocating said rod means to selected operating positions whereby electrical continuity is established between said input contact and one of said output contacts in each of said positions.

12. The switch according to claim 11 wherein said paths have substantially no attenuation at said signal frequencies.

13. The switch according to claim 11 wherein said means for reciprocating said rods are constructed so that said first rod may be moved independently of the other rods.

14. A coaxial microwave switch for use with a source of signals having frequencies within a certain frequency band, said switch comprising: at least one passage having a conductive wall, at least one rod mounted for axial movement within said passage, each rod having a plurality of spaced conductive sections separated from one another by a non-conductive section, at least one input means for connection to said source, said input means including a contact for engaging at least one of said conductive sections, a plurality of output means for connection to a plurality of load circuits, each of said output means including an output contact engaging said rod, and means for moving said rod into predetermined operating positions thereby connecting said input means via at least one of said conductive sections to selected ones of said output means, the walls of said passage surrounding each of said conductive sections providing a coaxial shield therefor and the walls of said passage surrounding said non-conductive sections being dimensioned to function as a wave-guide beyond cutoff with respect to signals within said certain band.

15. A coaxial microwave switch system including: a source of signals having frequencies within a certain frequency band, a load circuit, said source and load circuit having a certain characteristic impedance, and a coaxial microwave switch comprising: at least one passage having a conductive wall, at least one rod mounted for axial movement within said passage and having at least one conductive section, at least one input means connected to said source and including an input contact which engages said rod, at least one output means having an output contact which engages the conductive section of said rod, said output means being connected to said load circuit, and means for connecting said source and said load via said conductive section and via different circuit paths to characteristic terminating impedances in all of the operating positions of said switch, said connecting means including means for reciprocating said rod between predetermined operating positions, the walls of said passage providing a coaxial shield for said conductive rod section and being dimensioned to provide a wave-guide beyond cutoff with respect to signals within said certain band.

16. A coaxial microwave system comprising: a source of signals having frequencies within a certain frequency band, a microwave switch which comprises at least one passage having a conductive wall, at least one rod mounted for axial movement within said passage, each rod having a plurality of spaced conductive sections separated from one another by a non-conductive section, at least one input means connected to said source, said input means including a contact for engaging at least one of said conductive sections, means for reciprocating said rod in said passage in a plurality of operating positions, a plurality of output means each of which includes an output contact for engaging said rod; a plurality of load circuits connected to selected ones of said output means, a plurality of impedance elements connected to selected others of said output means, each element having the characteristic terminating impedance value for a different one of said load circuits, said load circuits and said characteristic impedance elements being arranged so that in a first of said operating positions a first of said load circuits is connected to said source through a first of said conductive sections while a second of said load circuits is connected to its characteristic terminating impedance element through a second of said conductive sections wherever as in a second of said operating positions said first load

circuit is connected to its characteristic terminating impedance element through said first conductive section while said second load is connected to said source through said second conductive section, the walls of said passage surrounding each of said conductive sections constituting a coaxial shield therefor and the walls of said passage not surrounding said conductive sections being dimensioned to function as a waveguide beyond cutoff with respect to signals within said certain band.

17. A coaxial microwave switching system comprising: a source of microwave signals having frequencies within a certain frequency band; a microwave switch having at least one passage having a conductive wall, at least one rod mounted for axial movement within said passage, each rod having at least spaced first and second conductive sections, at least one input means connected to said source and including an input contact for engaging said conductive sections, means for reciprocating said rod into first and second positions and first, second, third, and fourth output means having respective output contacts for engaging said rod; first and second load circuits respectively connected to said output contacts of said first and second output means; and first and second impedance

means respectively coupled to the contacts of said third and said fourth output means, said first and second impedance means respectively having values equal to the characteristic terminating impedances of said first and second load circuits, said first load being connected, via said first conductive section, to said source in said first position and to said first impedance means in said second position, said second load being connected, via said second section, to said second impedance means in said first position and to said source in said second position, the wall of said passage providing a coaxial shield for said conductive rod sections and being dimensioned to provide a waveguide beyond cutoff with respect to signals within said certain band.
